UNITED STATES PATENT OFFICE.

SAMUEL A. GOULD, OF CHICAGO, ILLINOIS, ASSIGNOR TO HENRY B. POLSDORFER, OF EVANSVILLE, INDIANA.

CRIMPING-MACHINE.

SPECIFICATION forming part of Letters Patent No. 256,475, dated April 18, 1882.

Application filed January 25, 1882. (No model.)

To all whom it may concern:

Be it known that I, SAMUEL A. GOULD, of Chicago, in the county of Cook and State of Illinois, have invented certain new and useful 5 Improvements in Crimping-Machines; and I do hereby declare the following to be a full, clear, and exact description of the invention, that will enable others skilled in the art to which it appertains to construct and use the same, reference being had to the accompanying drawings, and to letters of reference marked thereon, forming a part of this specification.

This invention relates to that class of crimping-machines that are employed in preparing 15 metallic facings for wash-boards, and is an improvement on Letters Patent No. 237,515.

This improvement consists more especially 20 of an attachment for throwing the machine proper in and out of gear, and at the same time forcing the prepared facing out from between the dies.

The general construction of the machine proper is the same as that in the patent above referred to, and the description in this case will 25 therefore be confined to the improved attachment.

Figure 1 is an end elevation, showing the 30 position of the mechanism composing the attachment when out of gear; Fig. 2, a view of the same when in gear; Fig. 3, a view of the opposite end of the machine; Fig. 4, a vertical transverse section in the plane 3 3, Fig. 5; Fig. 5, a view of the back side of the machine; Fig. 6, a horizontal section in the plane 6 6, 35 Fig. 5; and Figs. 7 and 8, detached details of construction.

Referring to the drawings, A represents the 40 supporting frame-work, and B the roller or shaft carrying the series of cams C. At that end of the machine illustrated in Figs. 1 and 2 of the drawings, and at the right hand of the operator, is located the vertical shaft B', which has both a lateral and a vertical movement, and has bearings in the brackets a', attached 45 to the frame-work A. On and near the upper end of the vertical shaft B' is placed the collar B², provided with the jaws a² a³. The upper jaw, a², is somewhat broader than the lower jaw, and as the lower or inner end of the op-

erating-lever B³ passes by the lower jaw it impinges against the under side of the upper jaw, a², when the mechanism is thrown into gear, as shown in Fig. 2 of the drawings.

The contact of the operating-lever B³ produces a vertical movement of the shaft B', and 55 at the same time releases the lower end of this shaft, which then receives a slight lateral movement in an outward direction from the machine proper, bringing the lower jaw, a³, immediately underneath the engaging end of the operating lever B³, thereby preventing these parts from becoming disengaged until properly released. The mechanism imparting the lateral movement to the shaft B' will be explained further along.

At a point near the lower end of the vertical shaft B' is placed the collar B⁴, provided with the projecting arm C'. Below this point, and on the same shaft, is the collar C², provided with the projecting arm C³. These collars are 70 set on the shaft so as to bring the integral projections at about right angles to each other.

To the outer end of the projection C' is pivoted one end of the short connecting-arm C⁴, (more clearly shown in Fig. 6 of the drawings,) 75 the other end being attached to the outer end of the bent shifting-lever D, the opposite end of this shifting-lever branching off into two parts, forming the yoke a⁴, one branch passing over and the other underneath the clutch-box 80 D', as shown in Fig. 8 of the drawings, the two branch ends joining again, and are bolted to the bracket b, attached to the back side of the frame A, as shown in Fig. 5 of the drawings.

The clutch D' is of the ordinary form of construction. The inner member, A', is feathered onto the horizontal shaft b', so as to permit of a slight longitudinal movement, while the other member, A², is rigidly attached to the band-pulley D², and revolves loosely with the 90 same on the shaft when the mechanism is thrown out of engagement and the machine proper is at rest. That part of the clutch recessed for the reception of the counterpart is provided with an annular groove, into which 95 fits the projecting bearings a⁵, attached to the inside of the yoke a⁴, as shown in Fig. 7 of the drawings. By this arrangement the clutch is

thrown in or out of engagement by a corresponding movement of the opposite end of the shifting-lever D.

On one end of the horizontal shaft B is the trip-cam D³, which is brought in contact with the projection C³ on the collar C² at each revolution, thereby throwing the mechanism out of gear. One end of the horizontal spring b² is connected to the projecting arm of the collar C², while the opposite end is attached to the bracket b³, secured to the back part of the frame-work, as shown in Fig. 5 of the drawings.

The operating-lever B³ is placed upon the cam-rod E, and has connection with the crank-arm E', located on the cam-rod E², by means of the connecting-bar E³. These cam-rods pass through the frame-work near the top and just immediately above the die-plate D⁴. As the operating-lever B³ is depressed to throw the machine into operation the cam-rods rotate far enough to bring the cam-projections F in contact with the upper side of the die-plate D⁴, forcing the same down to its proper position to be operated against by the lower dies. When the mechanism is thrown out of gear the die or crown plate D⁴ is returned to its normal position through the medium of the flat spring F', the ends of which rest upon the top of the frame-work, and the middle having connection with the center of the die-plate by means of the hook d and the eyebolt d'.

At the back side of the machine, as shown in Fig. 5 of the drawings, is placed the rock-shaft F², one end of which is bent at right angles to form the upwardly-projecting arm d². Attached to this rock-shaft at a point equidistant from the ends are the two circular arms d³, which take a downward course and have V-shaped notches in the ends. These arms pass in between the upper and lower dies or formers at each revolution of the machine and force out the corrugated sheet of metal, so that it may be conveniently removed. This operation is automatically performed by means of the crank-arm E' striking the upper end of the arm d² as the mechanism is thrown out of gear, rotating the rock-shaft, and throwing the arms d³ between the dies. The end of the rock-shaft bent upward to form the arm d² will be so weighted as to return the rock-shaft to its normal position by force of gravity when released from contact with the crank-arm E'. Force is given to the blow of the crank-arm E' and the mechanism assisted to return to a normal position by the vertical spiral spring F³, one end of which is connected to the crank-arm E' and the other end to the frame-work A.

Motion is imparted to the roller or shaft B by means of the pinion H, located on the opposite end of the shaft b' from the clutch-box D', which engages with the gear-wheel H, located on the shaft B.

The operation is as follows: Fig. 1 of the drawings shows the mechanism out of gear. It will be noticed that the forward or straight

side of the tripping-cam D³ rests against the projection C³, forming an integral part of the collar C². Now, by grasping the operating-lever B³ and bringing it to the position shown in Fig. 2 of the drawings the inner end of the lever comes in contact with the under side of the jaw a², which has the effect of raising the shaft B' just high enough to allow the cam D³ to pass under the projecting arm C³; at the same time the horizontal spring b² imparts a slight lateral outward movement to the vertical shaft B', which brings the jaw a³ under the inner end of the operating-lever. The same movement throws outward the end of the lever D by means of the arm C⁴, connecting the end of said lever and the projection C', which has the effect of throwing the clutch into gear by means of the yoke end of the lever D. When the shaft or roller B completes a revolution the tripping-cam D³ strikes against the projection C³, imparting a lateral inward movement to the shaft B', throwing the clutch out of engagement, and releases the inner end of the operating-lever from between the jaws a² and a³.

Having thus described my invention, what I claim as new, and desire to secure by Letters Patent, is—

1. In a crimping-machine, the combination, with the operating-lever B³, of the collar B², provided with the jaws a² a³, and the vertical shaft B', adapted to have both a lateral and a vertical movement, substantially as and for the purpose set forth.

2. In a crimping-machine, the combination, with the vertical shaft B', of the collar B², having the integral projection C', the connecting-arm C⁴, the shifting-lever D, provided with the yoke end a⁴, and the clutch D', substantially as described.

3. In a crimping-machine, the combination, with the operating-lever B³, of the collar B², having the jaws a² a³, the vertical shaft B', the collar B⁴, having the integral projection C', the connecting-arm C⁴, the shifting-lever D, provided with the yoke a⁴, and the clutch D', all constructed and arranged to operate as described.

4. In a crimping-machine, the combination, with the vertical shaft B', of the collar C², having the integral projection C³, the spring b², the tripping-cam D³, and the shaft or roller B, carrying the series of cams C, substantially as described.

5. In a crimping-machine, the combination, with the operating-lever B³, of the collar B² of the vertical shaft B', the collar C², having the integral part C³, the spring b², the tripping-cam D³, and the shaft or roller B, substantially as and for the purpose set forth.

6. In a crimping-machine, the combination, with the shaft or roller B, carrying the series of cams C, of the gear-wheel H', the pinion H, the horizontal shaft b', the clutch D', and the shifting-lever D, substantially as described.

7. In a crimping-machine, the combination, with the operating-lever B³, of the connect-

ing-bar E³, the crank-arm E', the spiral spring F³, and the arm d² of the rock-shaft F², substantially as and for the purpose set forth.

8. In a crimping-machine, the combination, with the die-plate D⁴, of the cam-rods E E², the crank-arm E', the connecting-bar E³, and the operating-lever B³, substantially as and for the purpose described.

9. In a crimping-machine, the combination, with the die-plate D⁴, of the eyebolt d', the hook d, and the spring F', as described.

10. The combination, with a crimping-machine, of the rock-shaft F², having one end turned upward at right angles to form the arm d², and carrying the downward-projecting arms d³, substantially as and for the purpose described. 15
